VACUUM CLEANER NOZZLE

Edward Stroschein, Oshkosh, Wis.

Application October 24, 1938, Serial No. 236,639

1 Claim. (Cl. 15—157)

This invention appertains to suction devices, and more particularly to a novel vacuum cleaner nozzle.

One of the primary objects of my invention is to provide a cleaner nozzle embodying a light, substantially flat suction head, and a combined manipulating handle and suction tube rockably mounted thereon, whereby said head can be conveniently manipulated in confined places and under articles of furniture, radiators, and the like.

Another salient object of my invention is to provide a vacuum cleaner nozzle having a plurality of orifices formed in the front portion thereof, whereby air will be caused to be violently drawn down through the nap of rugs and the like, and thence into the intake opening, and thereby effectively removing lint, hair, dirt, etc. from the article being cleaned.

A further object of my invention is to provide a novel open-throat connection between the suction head and the suction pipe, whereby the suction pipe can be conveniently swung on the head to any desired angle without loss of suction and without undue wear on moving parts.

A further important object of my invention is the provision of novelly arranged bar agitators or runner guides on the lower face of the suction head, the agitators or runners slanting back toward the intake opening to permit the free passage of air with the conveyed dirt into the suction hose, but at the same time preventing the rug or other article from sealing the intake opening.

A further object of my invention is to provide a flaring vacuum cleaner nozzle in which the air is drawn toward a centrally disposed intake opening, whereby a wide intake nozzle will be had in the front of the head, and a narrow nozzle at the back of the head, whereby the nozzle can be run over the edge of rugs and the like without loss of suction.

A still further object of my invention is to provide a nozzle for vacuum cleaners of the above character, which will be durable and efficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawings, in which drawings:

Figure 1 is a top plan view of my improved vacuum cleaner nozzle, showing parts thereof

broken away and in section, to illustrate structural detail.

Figure 2 is a side elevational view of my improved vacuum cleaner nozzle, showing parts thereof broken away and in section, illustrating the handle in full lines in its lowered position, and in dotted lines in its elevated position.

Figure 3 is a bottom plan view of the nozzle.

Figure 4 is a central, longitudinal, sectional view through the cleaner nozzle, taken on the line 4—4 of Figure 1, looking in the direction of the arrows, the view being taken on a larger scale than Figure 1.

Figure 5 is a transverse, sectional view through the intake pipe, the view being taken substantially on the line 5—5 of Figure 3, looking in the direction of the arrows, the view being on a larger scale than Figure 3.

Referring to the drawings in detail, wherein similar reference characters designate corresponding parts throughout the several views, the latter N generally indicates my improved vacuum cleaner nozzle, which comprises a suction head 10 and a combined manipulating handle and suction tube 11. The head 10 is formed relatively flat and can be either made from sheet metal suitably bent or stamped into shape, or can be formed from cast material.

The head 10 includes a triangular-shaped body 12 having a broad, upwardly curved leading edge 13. The body tapers rearwardly from said curved leading edge and terminates in a shoe 14. This shoe can also be provided with an upwardly curved flange 15, which acts as a stop for the downward swinging movement of the suction tube 11, as will be later set forth.

The body 12 adjacent the shoe 14 is provided with a transversely extending suction intake opening 16 surrounded by an upwardly extending, rearwardly directed throat 17. Upwardly extending, spaced, parallel side walls 18 are connected with the top surface of the body 12 and extend forwardly from the throat 17 and engage the opposite sides thereof. The rear edge of the throat 17 has formed thereon a hinge barrel 19 for the reception of a hinge knuckle 20 formed on the lower transverse edge of the suction tube 11. Thus, the suction tube 11 is free to swing back and forth on the head, and downward swinging movement of the suction tube is limited by its engagement with the upwardly curved flange 15. The upper forward edge of the tube 11 has formed thereon a hinge barrel 21, which receives a hinge knuckle 22 formed on the rear

edge of the sliding closure plate 23. This sliding closure plate rides between the side walls 18 and on the upper face of the head 12. The side edges of the closure plate 23 snugly engage the inner faces of the side walls 18. During the intake of air through the tube 11, the plate 23 will be drawn down into intimate contact with the upper face of the body 12, so as to form a seal therewith. If so desired, however, the side edge of the closure plate 23 can carry pins 24 for reception in slots 25 formed in the side walls 18. Thus, the plate 23 will be positively guided during swinging movement of the tube 11.

The rear or shoe portion 14 of the head can be formed relatively thick, or an extra piece of metal 26 can be secured to the lower face of the shoe. Extending forwardly from the piece 26 at the side edges of the head 10 are runners or guide ribs 27. These guide ribs terminate short of the front or leading edge of the nozzle. An inner pair of guide runners or ribs 28 is also carried by the lower face of the head, and these inner ribs or runners terminate in rear of the forward edge of the head, and are disposed on opposite sides of the longitudinal center of the nozzle and substantially at the same angle as the side ribs or runners 27.

Relatively long intermediate runners or ribs 29 are also carried by the head 10, and these long intermediate runners or ribs are disposed between the ribs 27 and 28 and terminate short of the front edge of the head. As shown, the ribs 29 extend back over the intake opening 16 and are arranged at a greater angle to the longitudinal axis of the nozzle than the ribs or runners 27 and 28.

Staggered rows of orifices 30 are arranged at the extreme front portion of the head and in advance of the ribs or runners 27, 28, and 29. All of these orifices open out through the top and bottom of the head, and their edges are provided with depending lips 31, which, in effect, form small guide nozzles and the lips terminating in the same plane as the lower faces of the ribs or runners for engaging the rug or other article being cleaned.

The combined suction pipe and handle 11 is preferably formed from sheet metal in any approved manner, and the same can terminate in a cylindrical tapered portion 32 for the reception of a flexible suction hose, which can extend to a suitable intake fan (not shown).

My nozzle is of an extremely light construction, and, thus, the same can be conveniently handled

and manipulated by an operator. The ribs 27, 28, and 29 form means for spacing the head from the rug or other surface being cleaned, and, thus, prevent the intake opening 16 from being sealed by a rug being lifted into the opening. The guide runners also act as agitators and entirely eliminate the use of rotary brushes and the like, as the runners slide over and agitate the pile of the fabric being cleaned.

The spacing of the guide runners or ribs form channels therebetween for the air, and a large intake is provided at the front of the nozzle, which narrows back toward the intake throat 11. By this arrangement, the suction through the nozzle is not broken, even where the front of the nozzle rides off a rug.

Great stress is laid on the orifices 30, as these orifices permit air to rush down through the nap of a rug or the like. Each orifice functions as a miniature blower nozzle, and lint, hair, thread, etc. is effectively picked up from the article being cleaned. The air moves down into the nap of the rug and then up into the nozzle.

The bar agitators or runner ribs increase the air velocity and dirt-getting and -carrying power directly from the orifice 30 to the intake 16 of the head. The nozzle will not clog, and all of the orifices are self-cleaning. As heretofore stated, the nozzle takes the place of brushes and moving agitators, which wear rugs and need re-pairing. All of the parts are open for inspection, and the entire nozzle can be readily cleaned.

The nozzle combines surface agitation with sealed suction cleaning, and, thus, the nozzle does both types of cleaning thoroughly and efficiently without floor drag, which tires the operator and wears out the nozzle. The nozzle will readily adjust itself to different depths of naps in rugs, etc., due to the novel construction thereof.

Changes in details may be made without departing from the spirit or the scope of this invention, but what I claim as new is:

A vacuum cleaner nozzle comprising, a substantially flat plate having an intake suction opening, a suction pipe communicating with said opening, said plate having orifices in the front end thereof opening out through the upper and lower faces thereof, surface-engaging agitating bars on the lower face of the plate extending from the orifices toward the suction opening, and depending lips surrounding the orifices terminating in the same plane as the lower faces of the bars for engaging the surface being cleaned.

EDWARD STROSCHEN.
